Primary Examiner — Michael C Stout*Assistant Examiner* — Melvin L Davis(74) *Attorney, Agent, or Firm* — Foley & Lardner LLP(57) **CLAIM**

We claim the ornamental design for a video game controller, as shown and described.

DESCRIPTION

FIG. 1 is a front-left perspective view from above of a portion of a video game controller according to another embodiment;

FIG. 2 is a left side view of the claimed design of FIG. 1; FIG. 3 is a right-side view of the claimed design of FIG. 1; FIG. 4 is a rear view of the claim design of FIG. 1; FIG. 5 is a front view of the claimed design of FIG. 1; FIG. 6 is a top view of the claimed design of FIG. 1; FIG. 7 is a bottom view of the claimed design of FIG. 1; and, FIG. 8 is a rear-right perspective view from below of the claimed design of FIG. 1.

The broken line showing of the video game controller is for the purpose of illustrating portions of the article and forms no part of the claimed design.
